UNITED STATES PATENT OFFICE.

SMITH F. PHILIPS, OF EL PASO, TEXAS.

SWITCH-STAND.

1,154,428.

Specification of Letters Patent. Patented Sept. 21, 1915.

Original application filed September 20, 1913, Serial No. 790,918. Divided and this application filed June 3, 1914. Serial No. 842,661.

To all whom it may concern:

Be it known that I, SMITH F. PHILIPS, a citizen of the United States, and a resident of El Paso, in the county of El Paso and 5 State of Texas, have invented a new and useful Improvement in Switch-Stands, of which the following is a specification.

My invention is an improvement in switch stands, and has for its object to provide 10 mechanism in connection with stands of the character specified for moving the points of a switch to deflect trains from the main track on to the switch, wherein locking mechanism is provided for locking the 15 switch points in safety or main line position and connected to the operating mechanism for moving the points in such manner that when the operating arm for the switch is moved into inoperative position after re- 20 turning the points to normal position, the locking mechanism will be operated to lock the points against movement.

In the drawings: Figure 1 is a perspective view of the improved stand. Fig. 2 is 25 a top plan view of a portion of a switch with the siding open and the locking mechanism with parts in section.

The present invention is a division of my prior application, Serial No. 790,918, filed 30 September 20th, 1913, issued as Patent No. 1,120,529, December 8, 1914, and the stand is of usual construction, comprising the table 1, having legs 2, which are supported by a plate 3, secured to a base block or extension 35 tie 4. The operating shaft 5 is journaled in the stand, and the said shaft is connected with the points 6 by means of a rod 6^a, the said rod being connected at one end to the points, and at the other to the crank 6^b at 40 the bottom of the shaft 5 for moving the same toward and from the main line rails 7, the said connection forming no part of the invention and for this reason not shown.

The shaft 5 is oscillated in the usual manner to move the points by means of a lever 8, and the lever is pivoted to the outer end of an operating arm 9, secured to the shaft above the table, the pivotal connection 10 being such as to permit the lever 8 to be 45 swung into alinement with the arm at which time it is free from the table or to be swung downward at right angles to the arm and engaging with notches 11 and 12, or for holding the levers and the points in open or 50 closed position.

Lugs 13 and 14 are connected with the table above the notches 11 and 12, and each lug 13 and 14 is provided with a slot for engagement by a perforated locking lug 15 on the lever. When the arm is swung downward as indicated in Fig. 1 into engagement with either notch 11 or 12, the lug 15 will pass through the slot of the adjacent lug 13 or 14 and the shackle of a pad lock is passed through the perforation of the lug 15 to lock the lever in the notch. 60

A pin 16 is arranged transversely of the upper end of the lever above the arm 9, and the upper face of the arm is provided with a transverse groove or notch 17 for receiving 70 the pin when the lever is in alinement with the arm. The pin 16 extends beyond the arm when in the notch, and is adapted to engage an opening 18 in a sliding block or plate 19, arranged adjacent to the notch 11, 75 and movable against a vertical extension 20 from the table.

The inner end of the sliding block or plate is pivoted to one of the arms 21 of a three- 80 armed rock lever, and the said arm 21 extends at right angles to the other arms 22 and 23, which are in alinement. The three- 85 armed lever is pivoted at 24 to the extension of the stand, and the arm 22 is connected with signal mechanism designated generally at 25 and forming the subject-matter of my before-mentioned copending application, of which the present case is a division. The arrangement is such that when the switch points are in safety position the signal is not 90 displayed, while when the points are in danger position the signal is displayed and the signal is operated by the same mechanism that moves the points. 95

The arm 23 of the rock lever is connected by a link 26 with one of the arms 27 of an elbow lever pivoted at 28 to the stand and having the other arm 29 thereof connected by a link 30 with the locking mechanism for the points. A casing 31 is connected with the base block 4 of the stand, and a locking plate 32 is slidably mounted in the casing. The locking plate is connected to the points by a link 33, the link passing through a perforated lug 34 on the adjacent point of the pair, and being engaged by a nut 35 on the opposite face of the lug from the locking plate to permit the parts to be adjusted with respect to each other. 100

The casing is provided with a transverse 110

opening and the locking plate 32 has an opening adapted to register with the opening of the casing when the points are in safety position, and the registering openings are 5 designed to be engaged by a locking pin 36. The pin 36 is pivoted to one arm of an elbow lever 37, the said lever having the arm 37 and an arm 38 arranged at approximately a right angle with respect to each other. The 10 elbow lever is pivoted to a lug 39, extending laterally outward from an extension 40 of the casing, and the link 30 connects the arm 38 of the elbow lever with the arm 29 of the elbow lever 27—29.

15 The operation of the improvement is as follows: When the switch lever 8 is raised into alignment with the arm 9 and out of engagement with the notch 12 of the stand, the said lever may be swung toward the sliding 20 block 19 to throw the points from side track to main line position. When the lever 8 is moved toward the locking lug 13 and just as the lever passes above the notch 11, the end of the pin 16 enters the opening 18 of 25 the sliding block or plate 19, and when the lever is pushed downward into engagement with the notch 11, the block or plate 19 is moved toward the locking lug 13. This movement of the block or plate swings 30 the three-armed rock lever in a direction to cause the arm 23 thereof to move downward. The link 26 communicates this movement to the elbow lever 27—28, and through the link 30 such movement is communicated to the 35 locking pin in a direction to cause the locking pin to move inward to engage the registering openings of the casing and the locking plate.

40 The switch points cannot move until the locking pin is withdrawn and the pin cannot be withdrawn until the switch lever is raised into alignment with the arm. When it is desired to open the switch, that is, to move the points to siding position the lever 45 8 must be lifted out of the notch 11 into alignment with the arm 9. Since the pin 16 is in engagement with the opening of the sliding block or plate the lifting of the arm moves the sliding block or plate away from 50 the locking lug 13, thus swinging the three-armed lever in a direction to cause the pin 36 to be withdrawn from the registering openings of the casing and the locking plate.

55 When the switch points 6 are set for the main line position, the pin 36 positively locks the plate and the points, so that even should the switch stand be torn from its position by a swinging door or the like, the points will remain locked and the main track 60 will remain clear.

I claim:—

1. In a switch stand, the combination with

the operating shaft journaled in vertical position in the stand and connected with the points for moving the points when the shaft 65 is oscillated, of an arm rigidly connected with the shaft at the table of the stand, a switch lever pivoted to the arm for swinging movement into and out of engagement with the notches of the table for holding the 70 shaft with the points in open or closed position, a rock lever pivoted to the stand, a block connected with one arm of the lever for sliding movement on the table adjacent to the notch engaged by the switch lever 75 when the points are closed, a cross pin at the inner end of the lever, the arm having a groove for receiving the pin to limit the upward movement of the lever, said block having an opening for receiving the pin 80 when the lever is in register with the notch with the points closed, a locking plate connected at one end with the switch points, a casing in which the other end of the plate engages, said plate and casing having openings registering when the points are in closed 85 position, a locking pin for engaging the openings to lock the plate, and a connection between the pin and the other arm of the rock lever for moving the pin from the 90 openings when the switch points are moved to open from closed position.

2. In a switch stand, the combination with the operating shaft journaled vertically in the stand and connected with the points for moving the same when the shaft is oscillated, of a lever mounted to swing into and out of horizontal position and connected with the shaft for oscillating the shaft, said stand having notches for receiving the lever 95 to hold the points open or closed, a rock lever pivoted at the stand, a locking plate connected with the points, a guide in connection with the stand, the plate being movable in the guide, said guide and plate having openings registering when the points are closed, a locking pin for engaging the openings, a connection between one arm of the rock lever at the stand and the locking pin for moving the pin into the openings when the locking lever is moved in one direction, a block 100 slideable on the stand adjacent to a notch, said lever having a cross pin and the block an opening for engagement by the pin when the lever moves into register with the 105 said notch, the other arm of the rock lever being connected to the block, said block being moved by the lever when it engages with the notch in a direction to engage the locking pin with the openings.
